DRAFT YOKE FOR RAILWAY CARS

George T. Johnson and Harry W. Stertzbach,
Columbus, Ohio, assignors to The Buckeye
Steel Castings Company, Columbus, Ohio

Application July 1, 1931, Serial No. 548,243

3 Claims. (Cl. 213—67)

This invention relates to improvements in draft yokes for railway cars, and more especially to a novel butt end for swivel draft yokes, which end will cooperate in a new way with the standard A. R. A. center brace and draft lug casting without interfering with such casting during travel in buff.

Many railway cars are now equipped with A. R. A. rigid shank couplers, cast steel yokes and combined center braces and rear draft lugs, and in order to obtain the advantages of the swivel type of coupler and yoke, it is desirable to replace the so-called rigid shank coupler and its horizontal keyed yoke with the swivel yoke and coupler. To make the change-over economical, as many of the old parts as possible should be retained, and that is one of the primary purposes of the present invention.

Those skilled in the art are aware that with the rigid shank coupler, the cast steel yoke does not travel rearwardly during buff, there being sufficient clearance between the rear end of the horizontal key (which connects the coupler shank and yoke) and the corresponding end of the yoke slot to accommodate the rearward travel of the key without moving the yoke. Therefore, if the swivel type is substituted for the rigid type, and the yoke must move rearward with the coupler during buff, there will be insufficient clearance between the butt end of the yoke and the standard A. R. A. center brace and draft lug casting. One might say that this could be remedied in a simple manner by merely cutting away or recessing the rear face of the yoke butt. However, this would not only weaken the butt end of the yoke, but there would be no means at the butt end to prevent said end from moving to a position in front of one or the other of the lugs of the standard A. R. A. center brace and draft lug casting. Consequently, it would be possible for the rear end of the yoke to be pushed over to one side or the other in the forward position, and to thus engage the front end of one of the draft lugs, thus preventing the release of the draft gear and the return of the yoke to its normal position. This would be a serious disadvantage.

Another object of the invention is to construct the yoke butt in such manner as to eliminate any liability of this disadvantage.

Another object is to provide a yoke butt of strong and light construction, and one having guide extensions to cooperate with the standard A. R. A. center brace and draft lug casting to

accommodate a change-over from the rigid type coupler to the swivel type.

With the foregoing objects outlined and with other objects in view which will appear as the description proceeds, the invention consists in the novel features hereinafter described in detail, illustrated in the accompanying drawings, and more particularly pointed out in the appended claims.

In the drawings,

Fig. 1 is a top plan view partly in horizontal section of the conventional draft sills of a railway car tied together by a standard A. R. A. center brace and draft lug casting, and showing the relation of those parts to the butt end of our improved draft yoke when the latter is in normal position.

Fig. 2 is a side elevation of the same, partly in vertical section.

Figs. 3 and 4 are views similar to Figs. 1 and 2, but showing the relation of the parts when the yoke is in its rearmost position.

Figs. 5 and 6 are views like Figs. 3 and 4, but illustrating the positions of the parts when the yoke is in its extreme front position.

Fig. 7 is a top plan view partly in horizontal section of a modification of the yoke butt.

Fig. 8 is an enlarged vertical sectional view of a portion of the modified form of yoke butt taken on the line 8—8 of Fig. 9.

Fig. 9 is a rear elevation of a portion of the modified butt.

As the invention in the present case resides especially in the butt end of the yoke and its relation to the standard A. R. A. center brace and draft lug casting, it is deemed unnecessary to illustrate the front end of the yoke. Said front end may be of any suitable construction to provide a swivel joint. For example, the forward end of the yoke and its connection to the coupler shank may be like that disclosed in the application of H. W. Stertzbach, J. S. McPherson and Arthur H. Filander, filed June 18, 1931, Serial No. 545,324, which matured into Patent No. 2,004,300, June 11, 1935.

Referring to the drawings, 10 designates the conventional center draft sills of a railway car, between which is interposed a standard A. R. A. center brace and draft lug casting 11 having the usual front vertical flange 12 and rear draft lugs 13.

In order that these parts may be retained when a change-over is made from a rigid shank coupler construction to the swivel type, the vertical yoke 14 of the swivel type mechanism is provided with

a special butt 15. The side edges of such butt are extended rearwardly to form vertical flanges 16 which extend throughout the height of the butt, and the medial portions of these flanges are 5 cut away as shown at 17 to provide recesses. This causes the corners of the butt to project rearwardly as at 18. In other words, the upper and lower ends of each flange 16 project rearwardly to a greater extent than the medial portions 10 thereof.

The thickness of the wall forming the butt is increased at the top and bottom, as indicated at 19, and for reinforcing purposes, horizontal ribs 20 extend across the butt end of the yoke 15 and merge into the flanges 16.

In Figs. 3 and 4, it will be noted that there is just sufficient clearance between the vertical flange 12 and the central portion of the butt end of the yoke to prevent contact between these 20 parts, when the yoke is in its rearmost position. At such times, the corners 18 project rearwardly above and below the flange 12.

The function of the corners or wings 18 is best 25 illustrated in Figs. 5 and 6, which show the yoke in its extreme forward position. In such position, the wings prevent the yoke butt from being pushed over in front of the lugs 13. Consequently, with our construction, the yoke will 30 always return to its normal position after the pull is released.

It will be seen from the above that if the usual 35 butt end construction were simply made shallower in order to accommodate a rearwardly travelling yoke to the A. R. A. center brace casting 11, it would be possible for the rear end of the yoke to be pushed over to one side or the other in the forward position so as to arrive in front of one of the lugs 13, thus preventing the 40 release of the draft gear and the return of the yoke to its normal position after the pull is released.

In the modification shown in Figs. 7 to 9 inclusive, the butt end is of substantially the same 45 construction as illustrated in the other figures with the main exception that the rear edge portions of the wings 18a are inturned as shown at 21 to provide beading around the rear edges of the wings.

From the foregoing it is believed that the 50 construction and advantages of our invention may be readily understood, and it is manifest that changes may be made in the details disclosed, without departing from the spirit of the invention, as expressed in the claims.

55 What is claimed and desired to be secured by Letters Patent is:

1. In a railway car having a center brace and draft lug casting with a front flange and forwardly directed lugs adapted to be used with a 60 connected coupler and yoke of the rigid type in which the coupler travels rearwardly independently of the yoke, means for using said car with a type of coupler and yoke in which the coupler and yoke move rearwardly in unison,

without disturbing the normal position of the said center brace and draft lug casting, said means comprising a yoke having a butt end provided at its sides with vertically disposed rearwardly projecting flanges, said flanges being tied together and having their medial portions recessed to accommodate the front flange of the casting, the upper and lower portions of said vertical flanges projecting rearwardly beyond said medial portions to operate between said lugs, the 10 lugs of the casting being positioned at opposite sides of said butt end and functioning as guides for the butt end. 5

2. In a railway car having a center brace and draft lug casting with a front flange and forwardly directed lugs adapted to be used with a connected coupler and yoke of the rigid type in which the coupler travels rearwardly independently of the yoke, means for using said car with a type of coupler and yoke in which the coupler 20 and yoke move rearwardly in unison, without disturbing the normal position of the said center brace and draft lug casting, said means comprising a yoke having a butt end provided at its sides with vertically disposed rearwardly projecting flanges, said flanges being tied together 25 and having their medial portions recessed to accommodate the front flange of the casting, the upper and lower portions of said vertical flanges projecting rearwardly beyond said medial portions to operate between said lugs, the inner surfaces of the projecting portions of said flanges extending toward each other rearwardly and inwardly, the lugs of the casting being positioned 30 at opposite sides of said butt end and functioning as guides for the butt end. 35

3. In a railway car having a center brace and draft lug casting with a front flange and forwardly directed lugs adapted to be used with a connected coupler and yoke of the rigid type in which the coupler travels rearwardly independently of the yoke, means for using said car with a type of coupler and yoke in which the coupler and yoke move rearwardly in unison, without disturbing the normal position of the said center 45 brace and draft lug casting, said means comprising a yoke having a butt end provided at its sides with vertically disposed rearwardly projecting flanges, said flanges being tied together and having their medial portions recessed to 50 accommodate the front flange of the casting, the upper and lower portions of said vertical flanges projecting rearwardly beyond said medial portions to operate between said lugs, the inner surfaces of the projecting portions of said flanges extending toward each other rearwardly and inwardly, and reinforcing ribs connecting the flanges to each other and to said butt end, the 55 lugs of the casting being positioned at opposite sides of said butt end and functioning as guides for the butt end. 60
